UNITED STATES PATENT OFFICE.

OTIS M. DRUSE, OF OMAHA, NEBRASKA.

PROTECTING-PLATE.

1,076,556.

Specification of Letters Patent.

Patented Oct. 21, 1913.

Application filed April 4, 1913. Serial No. 758,863.

To all whom it may concern:

Be it known that I, OTIS M. DRUSE, a citizen of the United States, residing at Omaha, in the county of Douglas and State 5 of Nebraska, have invented new and useful Improvements in Protecting-Plates, of which the following is a specification.

The present invention relates to protecting plates for switch or frog rails, and is 10 designed to provide a simple but effective means for preventing trainmen and others from having their feet caught between the said frog or switch rails, while attempting to pass over the same.

15 The improvement resides in the construction, combination and arrangement of parts set forth in the following specification and falling within the scope of the appended claim.

20 In the drawing there has been illustrated a satisfactory reduction of my improvement to practice, and in said drawing: Figure 1 is a perspective view illustrating my improvement in applied position between the 25 rails of a frog or switch, Fig. 2 is a transverse sectional view through the same, and Fig. 3 is a detail perspective view of one of the protector plates. Fig. 4 is a detail perspective view illustrating the protecting 30 plates arranged upon the ties and showing the end of a switch or frog rail disposed a suitable distance away from the main rail.

As is well known to track-walkers, track 35 construction and repairing men, the converging rails of a switch or frog are regarded as extremely dangerous to persons having occasion to walk the tracks or ties, for the reason that a person's foot is liable to become so wedged therein as to prevent the 40 ready withdrawal of the same, and upon numerous occasions persons having their feet so wedged and unable to remove the same in time to avoid an approaching train have had their wedged foot severed and 45 others in a like predicament have lost their lives.

With the knowledge of such conditions and circumstances, it is a primary object of this invention to provide a simple but thoroughly 50 effective device, which may be readily applied to the rails and which will effectively prevent such accidents.

Referring now to the drawing in detail, R--R designate the rails of a switch or frog 55 which are, of course, arranged at an angle with relation to each other to provide a

substantially V-shaped channel between the rails. The rails R have their base flanges secured to the ties T by the usual spikes S. It may here be stated that the channeled faces of the rails are greatly responsible for accidents, as above enumerated, occurring at the frog, as the foot of the person caught between the rails of the frog is tightly wedged against the opposite webs of the two rails R, and the ankle of the person is disposed between the inner faces of the heads of the rail, so that it is impossible to withdraw the foot by an upward movement, and thus it will be noted that to remove the impinged foot, it is necessary that the same be removed backwardly in a longitudinal direction in order that the space between the heads of the rails will be sufficient to permit of the upward movement of the foot. 70 I, therefore, provide protecting plates P--P for each of the opposite faces of the frog rails R, the said plates being of a desired length and extending rearwardly from the meeting points of the rails. These plates P 80 have their upper edges provided with flanges F which are adapted to lie beneath the heads of the rails R and to have their inner longitudinal edges contact with the webs of the rails when a pressure is exerted 85 upon the outer faces of the plates P. The opposite or lower longitudinal edges of the plates P are also flanged to provide what I will term the base members B of the plates. The base members B are adapted to underlie the base flanges of the rails R, and to be arranged upon the upper faces of the ties T. The plates P are constructed of spring metal, and their bent flanges F and G are adapted to exert an outward pressure, one 90 away from the other, and the flanges F engaging with the inclined underfaces of the rails exert a sufficient pressure or tension 95 against the said underfaces of the rails to sustain the same properly against said underfaces without the employment of other securing means.

In arranging the plates upon the rails after the frog has been laid or spiked to the ties T, it is merely necessary to withdraw 105 the spikes S, which engage with the inner or opposite longitudinal edges of the base flanges of the rails, to permit of the base portions B of the plates P being properly positioned. The spikes S are again driven 110 to within the ties T, but the offset portions of their heads are arranged away from the

base flanges of the rails, so that the said offset portions will not engage with and mutilate the plates P. To those skilled in the art, it is known that the ordinary spikes 5 S have their heads not only formed with a lip which normally overlies the base flanges of the rails, but the rear portion of said head is provided with a knob or bulging portion K, and this knob K sufficiently engages 10 with the lower face of the plate P to force the same tightly against the longitudinal edge of the rail R as well as partially overlying the said longitudinal edge and thus effectively sustain both the rail and 15 plate in proper position and against accidental displacement incident to the vibration occasioned by the rolling stock passing over the rails.

With a device as above described, it will 20 be noted that the plates P have their faces beveled or inclined, that is, the said plates have their upper edges arranged in a plane with the balls of the rails, and their lower edges arranged in a plane with the base 25 flanges of the rails, and the base flanges are of course extended at a greater distance

from the ends of the webs of the rails than are the heads, so that a person walking the tracks and having his foot placed within the plate may readily, with a slight exertion, remove his foot from between the plates. 30

Having thus described the invention, what I claim as new is:

A protector for frogs of railway rails, comprising a flat resilient plate having an upper inturned portion providing a flange which is adapted to underlie the head of the rail and to exert a tension upon the underface of the rail, the plate having its lower edge beveled to provide a resilient base member which is adapted to be arranged beneath the base flange of the rail and supported upon the ties which also support the rail, and means comprising a spike adapted to engage with the lower edge of the plate 40 for sustaining the plate against the rail. 45

In testimony whereof I affix my signature in presence of two witnesses.

OTIS M. DRUSE.
